UNITED STATES PATENT OFFICE

2,670,858

APPARATUS FOR FEEDING INDIVIDUAL BEARINGS FROM A STACK OF BEARINGS

Theodore R. Brink, Michigan City, Ind., and George D. Beaudry and John T. Longdon, Chicago, Ill., assignors to International Harvester Company, a corporation of New Jersey

Original application December 29, 1948, Serial No. 67,848. Divided and this application January 19, 1951, Serial No. 206,898

3 Claims. (Cl. 214—8.5)

1

This invention relates to a new and improved apparatus for removing individual bearings from a stack of bearings.

The present invention is a division of our pending patent application entitled Ball Bearing Washing Machine, filed December 29, 1948, and having Serial No. 67,848 and now Patent No. 2,654,378.

A principal object of this is to provide means for laterally feeding a single bearing from the bottom of a vertical stack of bearings.

An important object of this invention is the provision of an apparatus for removing a single bearing from the bottom of a vertical stack of bearings and wherein the remaining bearings in the stack are positively held in an elevated position during the removal of the lowermost bearing.

Another and further important object of this invention is to supply a positive feeding means for bearings from a vertically disposed stack of bearings without upsetting the stack or permitting any of the bearings in the stack to drop down into the path of movement of the lowermost bearing being removed.

Other and further important objects of this invention will become apparent from the disclosures in the following specification and accompanying drawing, in which:

Figure 1 is a top plan view of the feeding mechanism for delivering individual bearings from a stack of bearings.

Figure 2 is a side elevational view of the device as shown in Figure 1.

Figure 3 is an enlarged view of a portion of the feeding mechanism as shown in Fig. 1 and with the feeding mechanism in a shifted position.

Figure 4 is an end elevational view of the feeding mechanism taken on the line 4—4 of Fig. 2.

Figure 5 is a top plan view of the bearing magazine employed on the apparatus of this invention.

As shown in the drawings:

A bearing magazine 19 is adapted to receive and maintain a substantially vertical stack 20 of bearings 22. A feeding mechanism 21 is adapted to slide the bottom bearing of the vertical stack 20 without upsetting the other bearings in the stack and pushing it to a ball bearing treating machine such as a washing machine or the like.

The feeding mechanism 21 consists of a carrying structure 92. The carrying structure 92 extends beneath the magazine 19 and thus also beneath the vertical column 20 of bearings 22 to be washed. A vertical movable table or the like 93 is adapted in certain instances to support the

2

vertical column 20 of bearings 22. The member 93 has a downwardly extending shaft or piston member 94 journally mounted in the carrying structure 92 and, as best shown in Fig. 3, is provided with a roller 95 at its lower end adapted to be engaged by a cam member 96. The cam 96 is mounted for rotation on a shaft 97 supported by bearing brackets 98 depending from the carrying structure 92. In the position shown in Fig. 3, the member 93 is, in fact, supporting the column 20 of bearings 22 because the high surface of the cam 96 has pushed the piston 94 upwardly its maximum distance. The shaft 97 in addition to carrying the cam 96 also supports a pulley sheave 99 which is driven by a pulley belt 100 from some external source of power. Operation of the feeding mechanism thus depends upon rotation of the shaft 97 and thus also the cam 96 which controls the cycle of operations of the feeding mechanism elements. The pulley 99 is maintained in position by means of end thrust collars 101 and 102 also mounted on the shaft 97. An arm 103 is mounted on the shaft 97 for simultaneous rotation therewith.

A connecting link 104 joins the outer end of the arm 103 at 105 and at its other end is connected at 106 to a downwardly depending arm 107. The depending arm 107 is attached to the under side of a laterally sliding member 108 which is mounted for sliding movement beneath a pair of spaced ribs 109 and 110. The slide member 108 has mounted thereon a block member 111 carrying a vertical shank member 112 of a forwardly extending fork-like member 113. The shank member 112 is adjustably locked in the block 111 by means of vertical adjusting screw 114 and a horizontally disposed set or locking screw 115. The fork 113 is composed of a plurality of spaced fingers 116. The upper portion of the table member 93 is provided with a plurality of spaced vertical slots or notches 117 in and through which fork fingers 116 may freely pass.

The vertical column of bearings, as shown in Figs. 2 and 4, is supported on the fork member 113, and as especially viewed in Fig. 2 the ends of the fingers 116 are shown engaging the lower bearing in the stack of bearings 22 and pushing it along a receiving platform which in this instance is in the form of the track members 27 and 28 extending through a ball bearing treating machine or the like. If the fork member 113 were directly withdrawn, the column of bearings 22 would similarly be moved rearwardly with the fork member 113 and succeeding feeding of individual bearings from the bottom of a stack of

bearings would be prevented. Thus in order to accomplish withdrawal of the fork member 113 when shifting the position of the stack 20 of bearings 22 within the magazine 19, the table member 93 as shown in Fig. 3 is moved upwardly so that the fingers 116 of the feeding fork slide within the vertical slots 117 and the member 93 continues its upward movement so that the top surface thereof is slightly above the top surface of the fork member 113. At this point, the table member 93 assumes the load of the vertical column 10 of bearings and the fork member may be readily withdrawn without affecting the stability of the stack 20 of bearings 22.

Fig. 3 shows the fork member removed from its telescoping position within the table member 93. The cam 96 is shaped in such a manner that the table moves downwardly from its high position as shown in Fig. 3 to its lowermost position as shown in Fig. 2 prior to forward movement of the slide member 108. Immediately thereafter the slide member 108 and the feeding fork 113 move forwardly against the side of the lowermost bearing in the column 20 of bearings 22 pushing it onto the tracks 27 and 28 of fixed height, and inasmuch as the upper level of the fork 113 is substantially identical with the upper level of the lowermost bearing, there is no dropping of the stack of bearings when the one bearing at the bottom of the stack is moved into the bearing treating machine. The cycle of operations is then repeated with the table member 93 moving upwardly to support the column of bearings during that time when the feeding fork 113 is withdrawn to effect a succeeding feeding of bearings into the bearing treating machine.

As best shown in Fig. 5, the magazine 19 may be adjusted to accommodate various diameters of bearings. The magazine 19 consists of a supporting frame 118. The frame member includes spaced vertically disposed flange members 119 and 120 for supporting a right and left-hand screw 121. The screw 121 carries the magazine guide walls 122 and 123 which are angularly disposed in a substantially V-shape for easy insertion of bearings. The wall members 122 and 123 threadedly engage the screw 121 on different portions thereof so that upon rotation of the screw 121 by a knurled hand wheel 124, walls 122 and 123 are moved toward or away from each other as desired. The dash line positions of the walls 122 and 123 indicate the adjustment of the magazine for relatively small diameter bearings.

The apparatus of this invention is thus capable of efficiently removing the lowermost bearing from a vertical stack of bearings without in any way interfering with the bearings above the lowermost bearing being removed. Further with the apparatus employed herein there is no possibility of the upper bearings in a vertical stack of bearings coming down and interfering with the removal of the lowermost bearing because they are temporarily lifted and held out of position during the period of time of removal of the lowermost bearing. The apparatus of this invention may be effectively used with a ball bearing

washing machine such as shown in our parent application mentioned above and/or with any other of numerous bearing treating machines. Further it is not intended that the device of this invention be limited to the removal of individual bearings from a stack of bearings but it is contemplated that any article which may be stacked and individually removed would come within the scope of this invention. Alternative articles may be a plurality of disks wherein the lowermost disk is desired to be removed individually from a stack of such disks without disturbing the remainder of the stack.

Numerous details of construction may be varied throughout a wide range without departing from the principles disclosed herein, and we therefore do not propose limiting the patent granted hereon otherwise than as necessitated by the appended claims.

What is claimed is:

1. A device for singly and successively feeding bearings from a vertically disposed stack of bearings comprising a supporting structure, a table member having a downwardly depending piston journaled for vertical reciprocation in said supporting structure, a driven shaft carried on said supporting structure, a cam mounted on said driven shaft, a cam follower on the lower end of the depending piston of said table member, whereby the cam follower riding on the cam causes a raising or lowering of the table member carrying a vertically disposed stack of bearings, a bearing receiving platform disposed at a fixed height with respect to said supporting structure and positioned adjacent said table member, bearing pushing means slidably carried on said supporting structure and positioned adjacent said table member opposite said receiving platform, and means for moving said bearing pushing means across said table member to engage and push out a single bearing from beneath the stack of bearings, said bearing pushing means comprising a plurality of spaced, parallel, fork fingers, said table member having a plurality of vertically disposed slots through which the bearing pushing fingers may readily pass.

2. A device as set forth in claim 1 in which the fork fingers are disposed at a level substantially equal to the receiving platform.

3. A device as set forth in claim 2 in which the means for moving the bearing pushing means comprises a driving linkage from said driven shaft.
